(57) **CLAIM**

The ornamental design for a stylus for touch screens, as shown and described.

DESCRIPTION

FIG. 1 is a perspective view of a stylus for touch screens design showing my new design.

FIG. 2 is a front view of a stylus for touch screens.

FIG. 3 is a rear view of a stylus for touch screens.

FIG. 4 is a left side view of a stylus for touch screens.

FIG. 5 is a right side view of a stylus for touch screens.

FIG. 6 is an enlarged top view of a stylus for touch screens.

FIG. 7 is an enlarged bottom view of a stylus for touch screens; and,

FIG. 8 is an enlarged view of a stylus for touch screens taken from the circle part in FIG. 1.

The broken lines in the drawings depict portions of the stylus for touch screens that form no part of the claimed design.
